UNITED STATES PATENT OFFICE.

HERMAN I. GAHAGAN AND WILLIAM P. ARON, OF DALLAS, TEXAS, ASSIGNEES, BY
MESNE ASSIGNMENTS, TO THE WHISK RAZOR CORPORATION, OF BUFFALO, NEW
YORK, A CORPORATION OF NEW YORK.

RAZOR.

Application filed March 7, 1927. Serial No. 173,465.

This invention relates to razors and with regard to certain more specific features, to electrically operated safety razors.

Among the several objects of the invention may be noted the provision of an electro-magnetically operated safety razor, having a reciprocally operable blade whose motion, when compounded with the ordinary motions used in shaving, provides a desirable oblique cutting action; the provision of a reciprocally operable blade of the class described adapted to provide a desirable massaging effect to the skin as shaving proceeds; the provision of means for providing a maximum cutting stroke with a minimum armature action, said armature action and cutting stroke being adjustable; the provision of ready means for conveniently setting the razor for purely manual operation; and the provision of means of the class described which is simple, rugged and compact in design and dependable in operation, having a minimum number of moving elements easily assembled, said device being economical of manufacture. Other objects will be in part obvious and in part pointed out hereinafter.

The invention accordingly comprises the elements and combination of elements, features of construction, and arrangements of parts which will be exemplified in the structure hereinafter described, and the scope of the application of which will be indicated in the following claims.

In the accompanying drawings, in which is illustrated one of various possible embodiments of the invention,

Fig. 1 is a rear elevation of the razor;

Fig. 2 is a perspective view thereof, taken from the front and side;

Fig. 3 is a sectional view of the razor head taken substantially on lines 3—3 of Fig. 1;

Fig. 4 is a vertical section of the razor viewed from the rear;

Fig. 5 is a plan view of the lower section of a guard;

Fig. 6 is a perspective view of an upper guard section adapted to fit with the guard section of Fig. 5;

Fig. 7 is a rear elevation of the preferred form of blade used with and forming a part of the invention;

Fig. 8 is a plan view of said blade; and

Fig. 9 is a perspective view of a blade actuating element and armature. 55

Corresponding reference characters indicate corresponding parts throughout the several views of the drawings.

Referring now more particularly to Fig. 1, there is illustrated at numeral 1, a hollow handle composed preferably of a dielectric and non-corroding material such as bakelite, hard rubber or the like. This handle 1 has screwed thereto a head or cap 3, preferably composed of the same material and enclosing within the handle 1 an electromagnetic coil or solenoid 5. The coil 5 is provided with a suitable magnetic core 7, the upper end of which is screwed through said head 3, whereby the relative positions 70 of the handle 1 (including the head 3) and the core 7 may be adjusted. A set screw 9 is adapted to maintain any given adjustment. Suitably insulated current leads 11 are provided for the solenoid 5, passing out 75 of an opening 13 in the handle 1 and leading to a suitable source of alternating or interrupted current.

The head 3 is shaped to include an inclosing bracket portion 15, to which is held by 80 suitable screws 17, a lower guard 19. In some designs made under this invention it may be desirable to form the guard 19 as an integral portion of the head 3.

Held to said lower guard 19, by means 85 of another suitable set of screws 21, is an upper guard or cap 23 having a channel or groove 25 cut therein, for the purpose of slidably accommodating one side of a reinforcing rib 27 formed along the rearward 90 unsharpened edge of the blade B (see Figs. 2, 6 and 8). The other side of said rib 27 rests on the flat surface of the lower guard 19, while the steel blade 29 per se fits in a 95 sliding manner between a ridge 31 of said lower guard 19 and a spaced tongue 33 of said upper guard 23. As illustrated in Fig. 5, recesses 35 are formed in the lower guard 19, in order to enable a purchase to be had by a user on the blade 29 so that said blade 100 may be conveniently inserted and withdrawn when desired.

The blade B has the rib 27 pinched thereover. Its rear unsharpened edge is provided with two notches 37, one of which 105 during assembly becomes positioned in an

opening 39 formed in said rib 27. The openings 37, 39 in the blade B are unsymmetrically located. Two notches 37 are used in order that the blade and rib may be assembled in either of their two relative positions but only one opening 39 is used. The blade is suitably sharpened at its front edge 41. A small recess 43 at one end of the rib 27 permits the aforesaid purchase to be had on the blade when removal is desired. The finger nail of the user may be positioned in this recess 43 to accomplish the end in view.

In order to impart reciprocating motion to the blade B, when it is slidably positioned between the guards 19 and 23, a boss 45 is provided, forming an integral portion of said lower guard 19 at one end thereof. To this boss is fastened, preferably by means of a screw 47, a flexible springing magnetic armature 49.

The armature extends in a direction parallel with the underside of the guard 19 to a point adjacent the opposite end of said guard, the parallel portion being normally positioned in proximity to an outwardly positioned nose 53 of said solenoid core 7.

It is evident that the free portions of the spring armature 49 will be caused to vibrate when alternating, varying or interrupted current is applied through the solenoid 5. With the alternating or like current usually available, the vibration takes place at a rapid rate.

The purpose of vibrating the armature 49 is to reciprocate the blade B (with its rib 27); and in order to readily accomplish this end, an arm or finger 55 having a nose 57 is angularly turned up from the armature 49. This arm 55 (with its nose 57) is adapted to pass loosely through an opening 59 in the guard 19 and into a recess 61.

The notch 37 is normally positioned between the opening 59 and recess 61 where it is adapted to be engaged by said nose 57. Consequently, the vibratory action of the armature 49 in vibrating the nose 57, results in the blade B receiving a reciprocating movement between the guards 19 and 23. The opening 59 and recess 61 are of such dimensions as to freely accommodate the lateral movements of the arm 55 and nose 57.

One of the objects of this invention is to provide means for readily inserting and removing blades. For this purpose, a recess 63 is provided in the arm 55, just below the nose 57, which recess in normal operation of the razor is positioned below the notch 37, the nose 57 at this time engaging said notch 37. A downwardly directed finger 65, also a part of said armature 49 is so arranged that thereby the armature may be sprung upwardly when the said finger 65 is manually lifted. This action forces the nose 57 well into the recess 61 of the upper guard 23 and causes the recess 63 to register

with the blade members, 27, 29, whereby the blade members are in cleared position for unrestricted movement, out from between said guards 19 and 23. An analogous operation is performed in replacing another 70 blade.

It is evident that the relative adjusting movement possible between the armature 49 and the core 7 permits an operator to vary the blade stroke at will.

If, for any reason, the supply of current should fail at the leads 11, this razor may be readily converted to a non-reciprocating type by removing the blade in the manner above described and replacing it, after having changed its position end for end. The armature is maintained in its raised position during this operation. The reversal of the blade position takes the notches 37, 39 out of register with the openings 59, 61 and 85 consequently upon releasing the finger 65, the nose 57, instead of engaging said notch 37, engages the unnotched region 69 of the rib 27, thereby tightly pressing the blade into a shaving position.

It is evident from the above that the handle 1 and cap 3 form a case into which water will not readily enter, the opening 13 being at the bottom thereof. This case may be readily disassembled for purposes of replacing the solenoid or other parts and for the purposes of making adjustments. The bakelite or like composition of the guards resists undesirable heating and at the same time provides a light weight device.

It should be noted that the screws 47 form the virtual center for the vibratory action of the armature 49. The attracting nose 53 of the solenoid is closer to this center than the point of engagement between the nose 57 and the notch 37 and because the movement of points on a body movable with respect to a given center is directly proportional to the distance of the respective points to said center, the motion is multiplied. Hence, for a slight movement of the armature 49 at the nose 53, a considerable movement of the blade B is had.

In view of the above, it will be seen that the several objects of the invention are achieved and other advantageous results attained.

As many changes could be made in carrying out the above constructions without departing from the scope of the invention, it is intended that all matter contained in the above description or shown in the accompanying drawings shall be interpreted as illustrative and not in a limiting sense.

We claim:

1. The razor comprising a blade member, a handle and a head thereon for holding said blade, an armature adapted to be vibrated by means within the handle, said armature having a finger thereon which in normal posi-

- tion engages an opening unsymmetrically located in the blade member, a recess in said finger, the armature being manually movable to a sprung position wherein the recess and the blade member align, thereby permitting release of the blade and replacement thereof in its other position beneath said finger of the sprung armature, whereby upon manually releasing said armature said blade is non-reciprocally held in said head by the reaction of said finger of the sprung armature.
2. The razor comprising a blade member, a handle and a head thereon for holding said blade, an armature adapted to be vibrated by means within the handle, said armature having a finger thereon engaging an opening unsymmetrically located in the blade member, a recess in said finger, the armature being manually movable to a sprung position wherein the recess and the blade member align, thereby permitting release of the blade and a reversal of the position thereof in said head, said reversal resulting in the blade being non-reciprocally fixed in said head upon release of said armature.
3. The razor comprising a blade member, a handle and a head thereon for holding said blade, an armature adapted to be vibrated by means within the handle, said armature having a finger thereon engaging an opening unsymmetrically located in the blade member, a recess in said finger, the armature being manually movable to a position wherein the recess and the blade member align, thereby permitting release of the blade and a reversal of the position thereof in said head, said armature being resiliently mounted so as to react to hold the blade in position when the blade is reversed, so as to cause engagement of said finger with a portion of the blade having no opening.

In testimony whereof, we have signed our names to this specification this second day of March, 1927.

HERMAN I. GAHAGAN.
WILLIAM P. ARON.
